H. H. LAMPERT

T-HEAD

Filed Feb. 15, 1926

FIG. 3.

FIG. 2

Witness:

John S. Anderson,

Inventor

Henry A. Lampert,
By Hammer & Hammer,
Attys

UNITED STATES PATENT OFFICE.

HENRY H. LAMPERT, OF CHICAGO, ILLINOIS.

T HEAD.

Application filed February 15, 1926. Serial No. 88,250.

The main objects of this invention are to provide improved means for attaching a cross beam on the end of a post; and to provide improved means of this kind particularly adapted for securing together the parts of a T-head.

An illustrative embodiment of this invention is shown in the accompanying drawing, wherein:—

10 Figure 1 is a perspective view of a T-head to which this invention is applied, part of the cross beam being broken away for the sake of clearness.

Fig. 2 is a vertical section of the post cap, 15 taken on the line 2—2 of Fig. 1.

Fig. 3 is a similar view taken on the line 3—3 of Fig. 2.

In the specific form herein shown, the improved fastening means for securing the 20 cross beam to the post comprises a cap having a collar adapted to fit over the end of the post and having a seat on which the cross beam is supported.

The specific means for adjustably securing 25 the cap to the post is illustrated in my co-pending application, Serial No. 80,109, filed January 8, 1926, which shows a wedge supported in the collar of the cap in position to engage one face of the post. In the construction shown in said co-pending application, the post projects beyond the collar in position to directly support the cross beam.

In the device, to which the present invention is applied, the cap is provided with a 35 seat to which the cross beam is rigidly secured, so that the beam does not rest directly upon the post.

In the form herein shown, the T-head comprises an improved form of cap 1 mounted on the end of a post 2 for supporting a cross beam 3.

The improved cap 1 is preferably a metal casting having a collar 4 provided with a 45 socket which is slightly larger in cross section than the post 2, so as to permit it to be fitted over the end of the post. Extending across the top of the collar 4, is a base part 5, which forms a seat for supporting the cross beam 3. A portion of the base part 5 may be 50 cut away, as shown at 6, to decrease the weight of the cap. Arranged on opposite

sides of the base part 5, are flanges 7 which are adapted to embrace the cross beam 3. The cross beam 3 is rigidly secured to the cap by means of bolts 8 which extend 55 through apertures 9 formed in the base part 5. The lower portions of the apertures 9 are enlarged to provide seats 10 for the heads of the bolts. The bolts extend through the cross beam 3 and are provided with nuts 60 11 seated in recesses 12 formed in the top face of the beam.

Arranged in one wall of the collar 4, is a transversely disposed keyway 13 forming a seat for a wedge 14 which is adapted to be 65 driven into position for adjustably clamping the collar to the post 2.

In assembling this improved T-head, the cross beam 3 is first bolted to the cap 1 and the collar 4 is then placed over the end of 70 the post 2. By driving the wedge 14 into engagement with the post, the post and cap may be firmly and adjustably secured together.

Although but one specific embodiment of 75 this invention has been herein shown and described, it will be understood that certain details of the construction shown may be altered or omitted without departing from the spirit of this invention as defined by the 80 following claim.

I claim:

A cap for securing together the post and cross beam of a T-head comprising a collar having a socket adapted to receive one end 85 of the post, means on said collar for clamping said cap to the post, a bearing plate at the base of said socket forming a seat for the cross beam, bolts adapted to extend through said bearing plate and cross beam 90 for permanently securing said cap to the cross beam, the inner face of said bearing plate having countersunk apertures for the heads of said bolts, said bearing plate presenting an unobstructed surface for abutment against said post, and a pair of spaced flanges on said cap adapted to embrace the cross beam.

Signed at Chicago this 10th day of Feb. 1926.

HENRY H. LAMPERT.
